FUEL FEEDING APPARATUS FOR LIQUID FUEL BURNERS

Filed Aug. 16, 1927

Inventor:
George E. Goodridge,
3215 South Farney Avenue, Allentown, Pa.

UNITED STATES PATENT OFFICE

GEORGE E. GOODRIDGE, OF READING, MASSACHUSETTS, ASSIGNOR TO ARTHUR H. BALLARD, INCORPORATED, OF BOSTON, MASSACHUSETTS, A CORPORATION OF MASSACHUSETTS

FUEL FEEDING APPARATUS FOR LIQUID FUEL BURNERS

Application filed August 16, 1927. Serial No. 213,281.

This invention relates to fuel feeding devices for liquid fuel burners, being intended to provide a simple but effective arrangement for supplying such a burner with liquid fuel from a main fuel reservoir through the medium of a pump.

The invention will be best understood by reference to the following description when taken in connection with the accompanying 10 illustration of one specific embodiment thereof, while its scope will be more particularly pointed out in the appended claims.

The drawing indicates, more or less diagrammatically, a fuel feeding system for an 15 oil burner and the relation between the parts thereof to the main fuel reservoir and the burner.

Referring to the drawing and to the illustrative embodiment of the invention therein 20 shown, the liquid fuel burner comprises a burner nozzle 1 operatively related to the combustion chamber 3 of any suitable or usual form of heating device 5 and connected to the burner supply pipe 7 arranged to discharge 25 through the nozzle into the combustion chamber an atomized mixture of oil or other liquid fuel with air, the fuel being herein assumed for the purpose of illustration to be oil. To supply the burner a main reservoir or 30 supply tank 9 of relatively large capacity is provided, ordinarily located at a point away from the burner, and, in the case of tanks of large capacity, submerged in the ground.

The devices for delivering the air and oil 35 to the burner may be of any approved type, their specific construction not being particularly concerned with the present invention.

Heretofore for illustrative purposes I have shown fuel and air feeding devices of the type 40 closed in my prior Patent No. 1,631,859, dated June 7, 1927, the same comprising an auxiliary chamber or reservoir 11 of relatively small capacity located in proximity to the burner nozzle, there being contained within 45 the chamber a rotary atomizing pump (not shown) for delivering commingled air and oil from the chamber to the burner nozzle, and a second rotary suction pump indicated at 13 for delivering oil to the chamber from 50 the main tank or reservoir through a system

of conduits hereinafter described, together with regulating devices for maintaining a substantially constant level in the chamber.

The suction pump 13 is ordinarily located at a level below the highest level of the oil in the main reservoir 9, and it becomes desirable to provide such a system of connections between the pump and the reservoir as to prevent the creation of a siphoning action or the persistence of such a siphoning action 55 at such times as the pump is out of action so as to avoid the danger of flooding.

Herein the main reservoir 9, which is shown as provided with an air vent 15, has a reservoir suction pipe 17 entering through the top of the tank and having its open, lower end adjacent the bottom of the tank. The pipe 17, which has an intermediate portion 19 located above the highest level of the oil in the tank 9, is connected at its opposite end to a substantially air-tight receiving chamber 21 in the form of a standpipe, providing an air chamber of substantial capacity and of a cross sectional area greater than the effective cross sectional area of the reservoir suction pipe 17-19. The pipe 19 is herein connected to the standpipe 21 at the point above the level of the oil in the tank 9 through a connection 23 which provides an entrance 25 with flared walls, so that the oil leaving the pipe 19 flows into the enlarged dome-like space and tends to flow down the sides thereof and down the sides of the pipe 21.

The pipe 21 is arranged in a generally vertical position and has its open end entering within the settling chamber 27 of a greater diameter than that of the pipe, the side of the settling chamber being provided with an opening 29 having a removable cover which can be removed from time to time to withdraw 50 the dirt, sludge and other foreign material which accumulates therein. At a point 31 above the bottom of the settling space the settling chamber is connected to the pump suction pipe 33 which extends to the auxiliary chamber 11 and the suction pump 13, passing first through the separator 35 and thence through the pipe 37 to the pump intake 39. The latter is preferably at a point above the level of the point of connection 31 of the 55 100

- pump suction to the settling chamber so as to prevent any siphoning action, and the effective cross sectional area of the pump suction pipe 33 is no greater than that of the suction conduit 17-19, so that the capacity of the pump suction pipe to withdraw oil from the settling chamber and the enlarged standpipe 21 cannot exceed the capacity of the reservoir suction pipe to replenish the same.
- 10 With the parts constructed as described, the operation is as follows:
- When the suction pump starts into operation in the first instance, the settling space and the receiving chamber 21 are filled with air and devoid of oil. The first action of the pump is to exhaust the air therefrom, this action continuing until the pressure difference between the receiving chamber and the vented tank 9 is sufficient to cause the oil to pass over 15 from the vented tank through the reservoir suction pipe 17-19 into the receiving chamber. As the oil enters the receiving chamber it flows down the flared sides of the connection 23 and the sides of the standpipe and gradually accumulates in the settling chamber until it reaches the mouth of the pump suction pipe 33, whereupon the suction pump begins to withdraw oil from the separator space and deliver it to the auxiliary reservoir 11. As 20 the pump continues its operation, the oil will continue to flow from the tank to the standpipe until the mouth 31 of the pump suction pipe is covered and the pump begins to pump oil exclusively. Since the capacities of the 25 pump suction pipe and reservoir suction pipe are substantially the same, the amount of oil flowing into the receiving chamber will equal the amount withdrawn, and this balanced condition will be maintained so long as the 30 pump continues to operate at the full capacity of the suction pipe.
- If the oil flowing through the tank suction pipe 17-19 ceases for any reason, the oil level in the separator will drop and the suction 35 pump 13 will again withdraw air, lowering the pressure in the receiving chamber, until the flow from the tank is re-established.
- If, however, the operation of the suction pump 13 is stopped at any time, or if it fails 40 to operate at the full capacity of the suction pipe 33, the oil will accumulate in the standpipe until it rises to some level, such as that represented at 41, where it causes such an increase in the pressure of the residual air 45 contained within the standpipe as to stop the further flow of oil from the tank through the tank suction pipe 17-19 to the standpipe. The point to which the oil level must rise after the pump stops operation to bring 50 about this balanced condition will depend on the height to which the oil must be lifted from the tank through the tank suction pipe, as well as on the air capacity of the chamber 21, but the dimensions and relationships of 55 the various elements may be selected so that

no unduly high oil level in the standpipe need be reached.

When such balanced condition is reached, however, the pressure difference becomes insufficient to draw oil from the tank, all further flow of oil ceases and conditions in the separator and standpipe remain the same until the pump is again started into operation. This again lowers the oil level until the pressure of the air within the standpipe again reaches the point where the oil will flow from the tank to the separating chamber.

Accordingly, it will be seen that any siphoning action of the oil is prevented the moment the pump stops operation and at no 80 time is there maintained in the separating chamber and the standpipe an amount of oil sufficient to cause any siphoning between the latter and the suction pipe. The settling chamber provides an effective trap through 85 which all the oil must pass and from which the sludge, dirt and other impurities may be rapidly removed from time to time, and at the same time provides a small reserve body of oil below the level of which the 90 mouth of the pump suction pipe is normally submerged so that the pump is adapted to deliver oil to the chamber 11 as soon as it is started into operation.

While I have herein shown and described 95 for the purpose of illustration one specific embodiment of the invention, it will be understood that extensive deviations may be made therefrom and from the relative arrangement of parts, all without departing 100 from the spirit thereof.

What is claimed is:

1. In a liquid fuel feeding system, the combination with a main vented fuel reservoir, of a pump positioned at a level below the 105 level of the fuel in said reservoir, an intermediate, substantially air-tight, receiving chamber provided with a reservoir suction conduit having one end extending into said main reservoir, its opposite end connected to 110 said receiving chamber and an intermediate portion located above the fuel level in the main reservoir and having an effective cross-sectional area less than that of the chamber, the chamber being arranged to terminate at 115 its bottom in an enlarged settling space below the level of the pump intake and provided therewith a cleaning opening, and a pump suction conduit connected with said intermediate chamber at a point above the 120 bottom of said settling space but below the pump intake and having an effective cross-sectional area no greater than that of the reservoir suction conduit, thereby to prevent the 125 formation of a siphon through said intermediate chamber.

2. In a liquid fuel feeding system, the combination with a main vented fuel reservoir, of a pump positioned at a level below the 130 level of the fuel in said reservoir, an inter-

mediate, substantially air-tight, receiving chamber comprising a standpipe having its upper end above the level of the fuel in the reservoir and its lower end connected to an enlarged separating chamber extending below the level of the pump intake, a reservoir suction pipe of lesser feed capacity than the standpipe having an end connected to the upper end of the standpipe and its opposite end extending into the main reservoir, and a pump suction pipe connected to the receiving chamber at a point above the bottom of the separating chamber and below the pump suction and having a feed capacity no greater than that of the reservoir suction pipe.

5 In a liquid fuel feeding system, the combination with a main vented fuel reservoir, of a pump positioned at a level below the level of the fuel in said reservoir, a suction conduit between the pump and the main reservoir including an intermediate air chamber provided at its bottom with an enlarged settling space having a cleaning opening, a pump suction pipe connected to said chamber above the bottom of the settling space, and a reservoir suction pipe connecting the air chamber with the main reservoir and having a portion extending above the level of the fuel in the reservoir, the intermediate

20 air chamber having a greater feed capacity than that of the reservoir suction pipe, and the feed capacity of the pump suction pipe being no greater than that of the reservoir suction pipe.

25 3. In a liquid fuel feeding system, the combination with a main vented fuel reservoir, of a pump positioned at a level below the level of the fuel in said reservoir, a suction conduit between the pump and the main reservoir including an intermediate air chamber provided at its bottom with an enlarged settling space having a cleaning opening, a pump suction pipe connected to said chamber above the bottom of the settling space, and a reservoir suction pipe connecting the air chamber with the main reservoir and having a portion extending above the level of the fuel in the reservoir, the intermediate

30 air chamber having a greater feed capacity than that of the reservoir suction pipe, and the feed capacity of the pump suction pipe being no greater than that of the reservoir suction pipe.

35 4. In a liquid fuel feeding system, the combination with a main vented fuel reservoir, of a pump positioned at a level below the level of the fuel in said reservoir, a suction conduit between the pump and the main reservoir including a siphon breaking air chamber, a settling space connected therewith provided with means through which the same may be cleaned, and a pump suction connected with the settling space above the bottom

45 thereof.

5. In a liquid fuel feeding system, the combination with a main vented fuel reservoir, of a pump positioned at a level below the level of the fuel in said reservoir, a suction conduit between the pump and the main reservoir comprising an air-containing, siphon-breaking standpipe having a settling space at its bottom, a reservoir suction pipe extending above the fuel level in the main reservoir and connecting with the standpipe through a connection having flared walls, and a pump suction pipe connected to the settling space above the bottom thereof.

6. In a liquid fuel feeding system, the combination with a main vented fuel reservoir, of a pump positioned at a level below the level of the fuel in said reservoir, a suction conduit between the pump and reservoir including a siphon-breaking air chamber, a reservoir suction pipe connecting the main

reservoir with the upper part of said chamber and of lesser feed capacity than the chamber, a settling space at the bottom of the air chamber, a pump suction pipe also of lesser feed capacity than that of the air chamber connected to the settling space above the bottom thereof and at a point below the level of the pump intake.

In testimony whereof, I have signed my name to this specification.

GEORGE E. GOODRIDGE.
